FRAMED SCREEN

Henry C. Fosberg, Jamestown, N. Y., assignor to
 Watson Manufacturing Company, Inc., Jamestown, N. Y., a corporation of New York

Application April 27, 1942, Serial No. 440,591

9 Claims. (Cl. 160—383)

This invention relates to improvements in framed screens and more particularly to structures for mounting wire screen fabric in such frames.

In one form the invention is directed to the provision of means for securing the edges of wire screen fabric in a suitable channel provided therefor in the frame.

It is common practice in the manufacture of screens of the type to which the present invention is related, to mount the edges of screen fabric in a channel that opens on one face of the frame. The edge of the screen fabric bears against one side edge of the channel, projecting thereinto and being anchored by a rod or other member that is snapped or driven into wedging engagement with the channel walls. The screen fabric is required to be anchored under sufficient tension to be taut and held against bulging or sagging.

This means of anchoring the screen fabric in a frame is suitable except where unusual screen tension is required or in the use of special screen fabric. With special screen fabric such, for example, as the so-called Venetian blind type, it has been found that conventional anchoring means will not function satisfactorily. In this type of screen fabric, thin, flat strips are arranged horizontally, being spacedly connected by fine, vertically disposed, interwoven, wire strands. The vertical strands are of considerably greater spacing than are the horizontally disposed strips. The vertical edges of such screen fabric generally consist of cut ends of the thin, flat strips, and in many instances these strips may be anchored to the frame in the usual manner. The horizontal edges of this screen fabric, however, cannot readily be so anchored, since such edges consist of the widely spaced wire strands. The present invention, therefore, is directed to, and has for one of its objects, the provision of means for anchoring screen fabric edges under circumstances where conventional anchoring means is inadequate.

Another object of the invention is to provide means for anchoring screen fabric edges to a frame in a manner to avoid breakage of the relatively weak wire strands of which the screening is formed.

Another object of the invention is to provide means for mounting screen fabric in a frame without bending or folding the secured edges.

Other objects and advantages of the invention will be more fully understood from a consideration of the following specification, taken in con-

junction with the accompanying drawing; and in which

Figure 1 is a fragmentary front elevational view of a mounted screen in which is embodied one form of screen anchoring means;

Figure 2 is an enlarged fragmentary horizontal sectional view taken substantially on the line 2—2 of Figure 1, and shows a more or less conventional method of anchoring an edge of the screen fabric to a frame rail;

Figure 3 is an enlarged fragmentary vertical sectional view taken substantially on the line 3—3 of Figure 1 and shows a structure by which to anchor an edge of screen fabric without bending and wedging such edge into the frame channel;

Figure 4 is a fragmentary exploded view showing the method of assembling the structure of Figure 3;

Figure 5 is a fragmentary view taken substantially on the line 5—5 of Figure 3;

Figure 6 is a vertical sectional view showing a modification of the anchoring means; and

Figure 7 illustrates the invention as applied to conventional screen fabric.

Reference is now had to the drawing wherein the numeral 10 is employed to generally designate a screen embodying one form of the invention. In the present disclosure the frame of this screen is comprised of horizontal and vertical rail members 11 and 12, these members being identical in structure and consisting of tubular portions 13 having a channel 14 formed by an end wall of the tubular portion and a flange 16. It is found convenient to form the rail from sheet material, substantially as shown, and join the meeting edges by an overlapping flange 17, this flange also serving to provide a restriction to the open side of the channel.

It is contemplated to mount screen fabric 18 that, in one disclosed form, consists of thin, flat, horizontally disposed strips 19, arranged in any desired number to the inch, and being secured in uniform spaced relationship by vertically disposed interwoven wire strands 21. The strands 21, serving to position the strips 19, are preferably spaced a much greater distance apart than the strips, the extra spacing being optional but substantially as indicated in the drawing. The vertical edge of the screen fabric 18 consists of cut or free ends of the strips 19 and in many instances it is found both convenient and suitable to secure the vertical edge of screen fabric of this type to a frame rail in a more or less conventional manner. That is, by projecting the

free ends of the strip 19 into the channel 14 of the rail 12 and then inserting a rod or U-shaped member 22. The member 22 is so proportioned as to be snapped into and held in place by engagement with flange 17 of the channel side wall. When the member 22 is in place, the ends of the strips 19 are flattened and secured against the channel side wall.

With screen fabric of this type it is desirable to provide a different means for anchoring the horizontal edges, since these edges are formed by one of the strips 19 with only the twisted wire strands 21 holding it against displacement. To secure the horizontal edge of the screen fabric 18 there is provided an anchoring member 23, one form of which includes walls 24, 25, and 27. Wall 24 may include an outwardly projecting rib 28 or its equivalent which, when the member 23 is inserted into the channel 14, serves to spring-latch said member by engagement of the rib with an edge of flange 17. Wall 24 may terminate in a flange 29 and wall 27 in a flange 31. Flange 31 is formed with angularly disposed serrations, fingers, or teeth 32. Flange 31, before installation of the screen fabric, is disposed substantially as shown in Figure 4.

To secure the top and bottom edges of the screen fabric 18, such edges are projected into the space between flanges 29 and 31, substantially as shown in Figure 4, flange 31 then being bent into the plane of flange 29. As the position of this flange is changed, teeth or fingers 32 project into the space between a pair of strips 19, engaging the nearest strip, and those strips, between flanges 29 and 31, are bent to a position substantially as suggested in Figures 3 and 6. Thus, several of the strips 19 are clamped between flanges 29 and 31, and with the addition of fingers or teeth 32 the screen fabric edge is well anchored. It is to be kept in mind that all screen fabric must be mounted in the frame under considerable tension to prevent sagging or bulging during handling or use. In the present type this necessitates stretching the screen fabric at least $\frac{1}{8}$ " for every foot of height of screen. To produce this tautness with a screen in which the fabric has greater strength in one direction than in another, requires anchoring means that does not fracture or bend the weaker strands of the fabric. As may be clearly understood from the drawing, the interwoven strands 21 are not so distorted when they are clamped between flanges 29 and 31 as to be weakened to the point of breakage and, furthermore, since the strip 19, with which the fingers or teeth 32 engage, remains joined to the body of the fabric by strands that have not been disturbed whatsoever in the clamping or anchoring operation, there is no likelihood of the fabric pulling out from the top and bottom frame rails.

In Figure 6 of the drawing the serrations, fingers or teeth 32 are shown as formed on flange 29 of the member 23 rather than on flange 31. The function of these fingers or teeth is identical, however, with that already described.

In the disclosure of Figure 7 the fingers or teeth 33 are intended to be of a number and spacing to accord with the weave of conventional screen fabric 34, one tooth or finger 33 projecting into each interstice of the screen fabric. As distinguished from the conventional anchoring of the edge of screen fabric as shown in Figure 2, it will be noted that conventional screen fabric can be secured, through the use of anchoring means of the invention, to better advantage by reason of

the fact that the portion to be anchored is neither folded nor bent.

It is evident that the member 23 serves to both clamp and hook the screen fabric edge and that the serrations, teeth or fingers that serve as hooks may be varied as to size and number to accord with the particular mesh and type of fabric it is desired to anchor. Also that the dimensions of the anchoring member 23 may be varied as required for application to the channels of various screen frames. These variations or modifications, together with others, obvious to those skilled in the art, are therefore contemplated insofar as they are within the spirit and scope of the invention as defined in the annexed claims.

Having thus set forth my invention what I claim as new and for which I desire protection by Letters Patent is:

1. A structure for anchoring wire screen to a frame element comprising a walled member securable to said element, a pair of walls of said member providing a recess into which an edge portion of said screen projects, said walls being movable into close proximity to clamp said edge portion, and means on one of said walls projecting into interstices of said screen to have hooked engagement with a cross wire of said screen.

2. A structure for anchoring wire screen to a frame element comprising a walled member securable to said element, certain of the walls of said member being initially spaced apart to provide a recess into which an edge portion of said screen projects, said walls being movable into close proximity to engage and clamp said edge portion and extending in the direction of said screen, and means on one of said walls projecting through interstices of said screen and overlapping the edge of the other of said walls.

3. A structure for anchoring wire screen to a frame element comprising a tubular member, substantially parallel flanges at the meeting or seam edges of said member, an edge portion of said screen being positioned between said flanges, and angular projections on one of said flanges projecting into interstices of said screen and engaging a common cross wire of said screen.

4. A structure for anchoring screen to a frame element, the screen having parallel flat strips secured in spaced relationship by transversely disposed wire strands, said structure comprising a walled member securable to said element, a pair of walls of said member being initially spaced apart to provide a recess into which an edge portion of said screen projects, said walls being movable into close proximity with each other to engage said screen edge portion, and projections on one of said walls extending into the interstices of said screen to engage one of said flat strips.

5. A structure for anchoring screen to a frame element, the screen having parallel flat strips secured in spaced relationship by transversely disposed wire strands, said structure comprising a walled member securable to said element, a pair of walls of said member being spaced to provide a recess, an edge portion of said screen projecting into said recess and being engaged and clamped by said walls, and projections on one of said walls extending through interstices of said screen and overlapping the other of said walls, said projections having hook-like engagement with one of said flat strips.

6. A structure for anchoring screen to a frame element, the screen having parallel flat strips secured in spaced relationship by transversely dis-

posed wire strands, said structure comprising a walled member securable to said element, a pair of walls of said member being initially disposed to provide a recess, an unbent edge portion of said screen projecting into said recess and being engaged and clamped by said walls, the flat strips being somewhat distorted by the clamping action of said walls, angular projections on one of said walls extending through interstices of said screen beyond said walls, said projections having hook-like engagement with a flat strip adjacent those engaged by said walls.

7. A structure for anchoring wire screen to an open channel frame element comprising a tubular member, flanges at the meeting or seam edges of said member extending in the direction of application of said screen, an edge portion of said screen being between and adapted to be clamped by said flanges, projections on one of said flanges, said member, when mounted in the channel of said element, being somewhat collapsed to bring said flanges into clamping engagement with said edge portion and cause said

projections to extend into the interstices of said screen.

5 8. A structure for anchoring wire screen to a frame comprising a walled element associated with said frame, said element including a pair of initially spaced apart walls providing a recess into which an edge portion of said screen projects, offset means on at least one of the walls of said element, said walls being relatively movable into close proximity to clamp said edge portion therebetween and cause said means to interengage said screen.

10 9. A structure for anchoring wire screen to a frame comprising associated wall elements initially spaced apart to provide a recess into which an edge portion of said screen projects, offset means on at least one of said spaced apart wall elements, said elements being relatively movable into close proximity to engage and clamp an edge portion of said screen therebetween and cause said means to extend into the interstices of said screen.
